UNITED STATES PATENT OFFICE

SIDNEY SMITH, OF LYNCHCROFT, ENGLAND, ASSIGNOR TO LOUIS LINCOLN DRAKE, OF RIVERSIDE, CONNECTICUT

MILL FOR GRINDING PAINTS, ENAMELS, INKS, AND OTHER VISCOUS SUBSTANCES

Application filed March 20, 1931, Serial No. 524,179, and in Great Britain June 24, 1930.

The object of my invention is to provide an improved mill for grinding paints, enamel, ink and other viscous substances of the kind in which the material is ground between a rotating roller and a fixed grinding member.

In the usual mill of this kind the ground material is delivered to a receptacle open to the atmosphere and it is therefore liable to be contaminated by dust or other deleterious matter.

The object of the present invention is to produce a more efficient and economical mill and one in which dust and similar deleterious matter is excluded.

According to this invention the grinding roller is mounted and totally enclosed in the casing of the mill, so that the circumferential surface and ends are completely immersed in the material to be ground and the casing of the mill is provided with one or more completely enclosed outlet chambers adjacent to the periphery of the rotating roller. The stationary grinding members form the sides of the chamber and the adjustable grinding members and the scrapers are mounted in said chambers. The chambers are each provided with an outlet orifice, in order to remove the ground material.

If desired, an additional adjustable grinding member may be mounted in each chamber and is adjustable from outside the chamber.

A preferred form of my invention is illustrated in the accompanying drawings, in which—

Figure 1 is a side elevation of my grinding mill;

Fig. 2 is an end elevation of same;

Fig. 3 is a section on line 3—3 of Fig. 2; and

Fig. 4 is a view partly in end elevation and partly in section.

Referring to the accompanying drawings, I provide a suitable base 1 on which is mounted the cylinder or casing 2 of the machine. I provide completely enclosed outlet chambers 28 in which are suitable frames 4 in which are mounted adjustable grinding blocks 6 located or held in place by plates 3, as shown in Fig. 3. I also provide small coil

springs 8 bearing against the grinding blocks 6. I provide means whereby the adjustable grinding blocks 6 may be readily shifted into or out of agreement with the grinding roller 16, either by rods 7 attached to grinding blocks 6 and to the ends of which in turn the eccentric handles 9 are mounted, or by other suitable means such as by spring loaded adjustable screws with milled heads operated by hand from outside the chambers, whereby the blocks may be readily shifted into or out of engagement with the grinding roller 16. I also provide resiliently controlled scrapers 10 mounted on the suitable pivots or rods 11, and having shank extensions 12, to the ends of which are attached springs 13 which in turn are attached to the frame of the machine to hold the scrapers in contact with the surface of roller 16. I also provide suitable opposite fixed grinding members 14 as shown in Fig. 3 bearing against the surface of roller 16 which form the sides of the chamber.

I provide a suitable hopper 15 for the reception of the material to be ground and which discharges into the space 25 between the grinding roller 16 and the chambered cylinder or casing 2. The roller 16 totally enclosed in the cylinder or casing 2 of the machine, is affixed to a shaft 17 which is mounted in suitable bearings 18. Shaft 17 carries conventional driving pulleys 19, as shown in Figs. 2 and 4.

Attached to the cylinder or casing 2 are suitable spacing plates 21 to which are affixed the side plates 20. Mounted in plates 20 I provide adaptors 22 which carry balls 23 which bear against the opposite cam faces 24 of roller 16 and thus function to produce a longitudinally reciprocating movement of the roller 16 at the same time that it is being rotated. I provide opposite discharge outlets 26 for the discharge of the ground material, and also provide suitable lids or valves 27 to normally close the mouths of these outlets. It will be seen that after the material to be ground is placed in the hopper 15 it is completely enclosed until it emerges, ground, through the delivery or outlet pipes 26. It cannot therefore be contaminated by

the admixture of dust or other deleterious matter.

It will be obvious that the number and shape of the closed chambers 28 in which the scraper blades 10 are mounted may be varied as required and that suitable scrapers may be mounted in each chamber; also that the suitable removable covers or lids may be provided for the chambers 28.

I claim:

- 10 1. In a grinding mill of the type described, the combination of a casing, a roller mounted in spaced relation to the casing, and totally enclosed therein, the circumferential surface and ends of the roller being completely immersed in the material to be ground, a hopper arranged to empty material onto the roller, fixed grinding members in contact with the surface of the roller, spring pressed 15 adjustable grinding members adapted to be moved into or out of contact with the surface of the roller, eccentric handles operatively connected with said adjustable grinding members for manually adjusting same, 20 scrapers arranged to contact with the surface of the roller, and completely enclosed outlet chambers in which the aforesaid fixed and adjustable grinding members and scrapers are mounted, and outlet discharge members for the discharge of pulverized material.
- 25 2. In a grinding mill of the type described, the combination of a casing, a roller mounted in spaced relation to the casing, and totally enclosed therein, the circumferential surface and ends of the roller being completely immersed in the material to be ground, a hopper arranged to empty material onto the roller, fixed grinding members in contact with the surface of the roller, spring pressed 30 adjustable grinding members adapted to be moved into or out of contact with the surface of the roller, eccentric handles operatively connected with said adjustable grinding members for manually adjusting same, 35 resiliently controlled scrapers arranged to contact with the surface of the roller, and completely enclosed outlet chambers in which the aforesaid fixed and adjustable grinding members and resiliently controlled scrapers are mounted, and outlet discharge members for the discharge of pulverized material.

- 40 3. In a mill for grinding paints, enamels, inks and other viscous substances, the combination of a casing, a hopper in said casing, a grinding roller mounted and totally enclosed in the casing whereby the circumferential surface and ends are completely immersed in the material to be ground, grinding members bearing on the roller, and completely enclosed outlet chambers positioned in the casing and spaced from the hopper, the grinding members being mounted in said outlet chambers.
- 45 4. In a grinding mill of the type described, the combination of a casing having a hopper,

a grinding roller, stationary grinding members bearing on the roller, scrapers, outlet chambers in which the aforesaid grinding members and scrapers are mounted, the roller being mounted and totally enclosed in the 70 casing whereby the surface and ends of the grinding members are completely immersed in the material to be ground, the continuity of the casing being broken at the points where the hopper and outlet chambers are placed. 75

5. In a grinding mill of the type described, the combination of a casing, a hopper positioned in and breaking the continuity of the casing, a grinding roller mounted and totally enclosed in the casing the circumferential surface and ends of the roller being completely immersed in the material to be ground, spaced outlet chambers substantially enclosed in and breaking the continuity of the casing, and adjustable grinding members bearing on 80 the roller and mounted in the outlet chambers. 85

6. In a grinding mill of the type described, the combination of a casing having a hopper chamber, a grinding roller mounted and totally enclosed in the casing, the circumferential surface and ends of the roller being completely immersed in the material to be ground, completely enclosed outlet chambers, fixed grinding members mounted in 90 said outlet chambers and bearing on the roller, adjustable grinding members mounted in said outlet chambers and arranged for manual control, the continuity of the casing being broken at the points where the hopper and 95 outlet chambers are placed. 100

7. In a grinding mill of the type described, the combination of a casing having spaced hopper and discharge chambers breaking the continuity of the casing, a roller mounted 105 and totally enclosed in the casing, the circumferential surface and ends of the roller being completely immersed in the material to be ground, said roller having opposite end cam faces, stationary elements contacting with the end cam faces of the roller to cause same to reciprocate longitudinally, stationary grinding members positioned to form the sides of the discharge chambers and bearing on the surface of the roller, and adjustable 110 grinding members mounted in the discharge chambers and adapted to be shifted into or out of contact with the surface of the roller. 115

8. In a grinding mill of the type described, the combination of a casing, a hopper placed in the casing, a roller mounted and totally enclosed in the casing, the circumferential surface and ends of the roller being completely immersed in the material to be ground, said roller having opposite cam faces on its 120 ends, stationary elements contacting with the cam faces of the roller to cause same to reciprocate longitudinally, stationary grinding members in contact with the surface of the roller, adjustable grinding members mounted 125 130

in the discharge chambers and adapted to be shifted into or out of contact with the surface of the roller, resiliently controlled scraper members mounted in the discharge chambers and bearing against the surface of the roller, said scraper members being diagonally disposed at opposite positions of the rollers, and completely enclosed outlet chambers breaking the continuity of the casing and spaced from the hopper on opposite sides of the casing.

SIDNEY SMITH.
